US00D814929S

(12) **United States Design Patent** (10) **Patent No.:** **US D814,929 S**
(45) **Date of Patent:** **** Apr. 10, 2018**

(54) **PACKING TRAY**

(71) Applicant: **Tekni-Plex, Inc.**, Wayne, PA (US)

(72) Inventors: **Mark A. Bergeron**, Monroe, GA (US);
Babu Kuruvilla, Griffin, GA (US)

(73) Assignee: **Tekni-Plex, Inc.**, Wayne, PA (US)

(**) Term: **15 Years**

(21) Appl. No.: **29/587,073**

(22) Filed: **Dec. 9, 2016**

(51) LOC (11) Cl. **09-03**

(52) U.S. Cl.

USPC **D9/456**

CLAIM

The ornamental design for a packing tray, as shown and described.

DESCRIPTION

FIG. 1 is a top right perspective view of a packing tray according to our new design.

FIG. 2 is a top plan view thereof.

FIG. 3 is a right end elevational view thereof.

FIG. 4 is a left end elevational view thereof.

FIG. 5 is a front elevational view thereof.

FIG. 6 is a rear elevational view thereof; and,

FIG. 7 is a bottom perspective view thereof.

1 Claim, 3 Drawing Sheets
